[57] CLAIM

The ornamental design for a fuel dispensing unit, as shown and described.

DESCRIPTION

FIG. 1 is a right front perspective view of a fuel dispenser showing our new design;

FIG. 2 is a front elevational view thereof;

FIG. 3 is a right side elevational view wherein the left side is similar in appearance to the right side;

FIG. 4 is a left rear perspective view thereof;

FIG. 5 is a top plan view thereof; and,

FIG. 6 is a bottom view thereof.

The broken line showing of a fuel dispenser and hoses, in FIGS. 1-4 and 6 and partial hoses in FIG. 5 are for illustrative purposes only and forms no part of the claimed design.
